Primary Examiner — Kimberly Barnes(74) *Attorney, Agent, or Firm* — Cislo & Thomas, LLP(57) **CLAIM**

The ornamental design for an air conditioned hard hat, as shown and described.

DESCRIPTION

FIG. 1 is a perspective view of an air conditioned hard hat showing my new design;

FIG. 2 is a bottom perspective view of the air conditioned hard hat of FIG. 1;

FIG. 3 is a front elevation view of the air conditioned hard hat of FIG. 1;

FIG. 4 is a rear elevation view of the air conditioned hard hat of FIG. 1;

FIG. 5 is a right side elevation view of the air conditioned hard hat of FIG. 1;

FIG. 6 is a left side elevation view of the air conditioned hard hat of FIG. 1;

FIG. 7 is a top plan view of the air conditioned hard hat of FIG. 1; and,

FIG. 8 is a bottom plan view of the air conditioned hard hat of FIG. 1.

The broken lines shown in the drawings illustrate portions of my air conditioned hard hat that form no part of the claimed design.
